UNITED STATES PATENT OFFICE.

MARTHA M. PRINDALL, OF LYNN, MASSACHUSETTS.

WOMAN'S CURTAIN-DRAWERS.

1,102,800.

Specification of Letters Patent.

Patented July 7, 1914.

Application filed March 28, 1913. Serial No. 757,458.

To all whom it may concern:

Be it known that I, MARTHA M. PRINDALL, a citizen of the United States, resident of Lynn, in the county of Essex and State of Massachusetts, have made a certain new and useful Invention in Women's Curtain-Drawers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 The object of the invention is to provide drawers suitable for the protection of expensive skirts in women's dress, and it consists in the novel construction and combinations of parts, as hereinafter set forth.

20 In the accompanying drawings, illustrating the invention, Figure 1 is a plan view of the blank or pattern for the drawers; Fig. 2 is a plan view of the drawers spread out in flat position, and Fig. 3 is a central 25 vertical section of the drawers.

The pattern is in very simple form, whereby the entire pair of drawers, except the facings, are designed to be cut in one piece. In this pattern the leg portions, indicated in the 30 accompanying drawings, illustrating the invention by the numeral 2, extend in opposite directions in the flap from the middle or body portion 3, which is provided with a front U-shaped bay or cut-out 4 for the 35 waist, and with a rear flap or curtain 5 between rear bays or recesses 6, these rear recesses being opposite the fronts or placket edges of the drawers, indicated at 7. The placket edges are in line with each other and 40 at right angles, substantially, to the end portions of the waist bay. The waist bay is entirely cut out of the upper or front portion of the pattern and its ends form an angular junction with the ends of the 45 placket edges 7, which are in line with each other and form portions of the upper edge of the pattern. The rear or lower edge of the pattern is so cut that the curtain portion 5, is substantially below the rear seam edges of the leg portions. The curtain is 50 therefore not confined by junction with the waist bay, but hangs freely from the ends of the leg seams.

In cutting the goods the outer or free edge 8 of the flap should be taken on the selvage, a selvage edge being much preferable along this part, not only to facilitate laundering, but also to avoid inconvenience in the use of the garment, which would be apt to arise from a hemmed edge in this position.

In making the garment the waist recess or bay 4 is provided with the usual reinforcement, a band as at 9, and the recesses or cut-outs 6, adjoining the ends of the curtain edge are also reinforced, as indicated at 10. The front edges 7 are also reinforced. The front and rear edges 12 of each leg are stitched together in a suitable manner to form leg seams, and such lace or other ornamental trimming may be applied as the taste of the wearer may indicate.

The drawers are easily laundered, being doubled flat lengthwise, and have a continuous rectilinear fold extending from end to end of the leg portions through the middle portion, which is integral or solid, the waist bay being entirely in front of this line. The curtain and plackets, being connected to the leg seams, there is a tendency to draw the lower portion of the curtain inward, and in this way to aid the purposes of the article. When the drawers are longitudinally folded, the plackets are parallel to the line of the fold. In the use of these drawers, the edges of the cut-outs or recesses 6, being most subject to wear, are strengthened by reinforcing as indicated. The free curtain portion is designed to fall or hang in rear being somewhat drawn forward or inward below, in such wise as to protect the skirt or other garment behind it from being stained, especially in sitting down, through the unexpected appearance of the menses. A pair of drawers of this kind may also be made in several pieces, but by making the article of one piece the extra goods provided for in the curtain portion is so disposed as to avoid the inconvenience of unnecessary seams and folds.

100 What I claim is:

A pair of drawers, including a solid middle portion and oppositely extending leg portions, and having a continuous rectilinear fold of said middle portion and leg portions, a waist bay entirely in front of said

fold, and having its ends substantially at right angles to the line of said fold, a certain portion, lateral indentations in connection therewith, and plackets, parallel to the line of said fold, and connecting the ends of the waist bay to the ends of said indentations, at the ends of the leg seams.

In testimony whereof I affix my signature, in presence of two witnesses.

MARTHA M. PRINDALL.
